UNITED STATES PATENT OFFICE

FRANK C. FROLANDER, OF ELIZABETH, NEW JERSEY, ASSIGNOR TO MERGENTHALER LINOTYPE COMPANY, A CORPORATION OF NEW YORK

SLUG CASTING MACHINE

Application filed August 26, 1931. Serial No. 559,384.

This invention relates to slug casting machines, wherein printing slugs or type bars are cast in a slotted mold and delivered by an ejector advancing from the rear against 5 the edge of the slug. In these machines, the molds are adjustable in length to produce slugs of different lengths, as for printing columns or pages of different width, and the ejector employed is therefore constructed so 10 that it may be varied in width to correspond with changes in the length of the mold slot.

For instance, as illustrated in U. S. Letters Patent to John R. Rogers, No. 967,976, there 15 is commonly employed a composite ejector comprising a series of blades arranged edge to edge in contacting relation, and suitable devices whereby any desired number of blades can be connected with the ejector slide while the others are left free and remain at rest. 20 These ejector blades are quite thin, being made so to serve for the ejection of very thin slugs, as well as of the thicker slugs.

In recent years, there has been a growing 25 tendency to increase the thickness of the printing slugs and to such extent that the ejector above described is sometimes found to be incapable of ejecting the slugs from the molds in a thoroly satisfactory manner. Thus, it frequently happens that the ejector, 30 because of its thinness, will embed itself in the bottom edges of the slugs and fail to eject them fully from the mold, or that, because of undue resistance offered by the slugs, the ejector blades or other parts of the machine 35 will be damaged in the act of ejection. These objections arise particularly with the larger or thicker slugs, which are of the ribbed variety, i. e., comprise a solid body portion, an overhanging type-carrying portion, and a series of ribs cast on the body portion and giving support to the overhanging portion.

In the ejection of such ribbed slugs, the 40 ejector is arranged to engage only with the solid body portion, and since such portion 45 is located well to one side of the central plane of the slugs, the latter have a tendency to cant or tilt in the mold and thereby offer greater resistance to ejection than in the case of thinner slugs whose body portions are located close to or in the central plane.

The present invention is intended to overcome these and other objections and contemplates an ejector which may not only be adjusted in width, but which may be adjusted in thickness as well, so as to be capable of 55 cooperating with slugs of all dimensions, whether long or short or thick or thin. In the specific embodiment illustrated, the ejector proper is made up of two sections, one a main section comprising a series of vertically disposed blades arranged edge to edge in contacting relation, and the other a supplemental section comprising a series of blades disposed horizontally in superposed parallel relation alongside the main blades. 65 Both ejector sections are operated from a common actuating slide, means being provided for connecting the main section alone or both sections conjointly to the slide, as required. 70

Thus, when casting thin slugs, the main 75 ejector section is used alone, the blades of this section, due to their thinness and vertical disposition, being capable of ejecting such thin slugs; whereas, when casting thicker slugs (which as before stated are usually of the ribbed variety), both the main section and the supplemental section are used together, the main set of blades being arranged to engage the slugs by their solid body portions, 80 and the supplemental set of blades being arranged to engage the slugs by their ribbed portions. In this way, as will be readily apparent, the effective thickness of the ejector may be changed at will to correspond to the 85 thickness of the slugs being cast.

In a second embodiment illustrated, the 90 ejector is shown as comprising a second supplemental section (or three sections altogether), this further supplemental section comprising a series of blades arranged horizontally edge to edge with the blades of the first supplemental set. By the use of such a third set of blades, three different thicknesses of ejector are available. Of course, if desired, even a greater number of sections could be employed. 95

In both embodiments, provision is also made for varying the width of the ejector sections to correspond to the varying lengths. 100

of the slugs to be cast. This is accomplished by connecting any selected number of blades of the main section to the actuating slide while leaving the remaining blades free or disconnected from the slide. The variation in width of the supplemental section or sections is accomplished in the same way, means being employed to effect the necessary adjustments of all sections simultaneously or at one operation.

In the example illustrated, the selection of blades of the main set is controlled by a main vertically adjustable bar which can be set in different vertical positions to vary the number of blades operatively connected to the actuating slide, and the selection of blades of the supplemental set or sets is controlled by a supplemental vertically adjustable bar or bars which, like the main bar, can be set in different vertical positions to vary the number of blades operatively connected to the actuating slide. These vertically adjustable bars are movable with the actuating slide, being slidably supported upon a vertically adjustable rod which determines their vertical set position, but the supplemental bar or bars is or are mounted on the supporting rod so that it or they can be adjusted relatively to the main bar, and it is by means of this relative adjustment that the supplemental set or sets of blades is or are connected to and disconnected from the actuating slide irrespective of the adjusted position of the main bar.

To be more specific, and for the sake of clearness confining the description here to the first embodiment, the two vertically adjustable bars (main and supplemental) are formed in one of their side faces with thru-cuts or grooves which are adapted to be moved into or out of register according to the relative adjusted position of the two bars. When the grooves are in register, the two bars will clear the ejector blades of the supplemental section and hence free that section from connection with the actuating slide; whereas, when the grooves are out of register, the supplemental bar will, when the actuating slide moves forward, pick up the blades of the supplemental section (according to its vertically adjusted position) and hence establish an operative connection between such blades and the actuating slide.

In the accompanying drawings, the invention has been shown merely in preferred form and by way of example, and obviously many changes and modifications may be made therein and in its mode of application without departing from the spirit of the invention. It should be understood, therefore, that the invention is not limited to any specific form or embodiment except insofar as such limitations are specified in the appended claims.

Referring to the drawings:

Fig. 1 is a side elevation, partly broken

away, of an ejecting mechanism constructed in accordance with the invention;

Fig. 2 is a similar view on a slightly enlarged scale taken from the opposite side;

Fig. 3 is a longitudinal section, taken on the line 3—3 of Fig. 2, showing the ejector in its rearward or retracted position;

Fig. 4 is a similar section showing the ejector in its forward or projected position;

Fig. 5 is a vertical section, taken on the line 5—5 of Fig. 2, showing the vertically adjustable bars set for the connection of both the main and supplemental ejector sections to the actuating slide;

Fig. 6 is a similar vertical section, but showing the vertically adjustable bars set for the connection alone of the main ejector section to the actuating slide;

Fig. 7 is a vertical section, taken on the line 7—7 of Fig. 2, showing the connection between the main and supplemental ejector sections when both are in use;

Fig. 8 is a sectional side elevation of a modification, illustrating the use of two supplemental ejector sections;

Fig. 9 is a vertical section, taken on the line 9—9 of Fig. 8, and showing both supplemental ejector sections disconnected from the actuating slide;

Fig. 10 is a section, taken longitudinally thru the ejector of Fig. 8, looking downward or from the top;

Fig. 11 is a view similar to Fig. 9, but showing the vertically adjustable bars set for the connection of the main set and the first supplemental set of ejector blades to the actuating slide, the second supplemental set of blades being disconnected therefrom; and

Figs. 12, 13, and 14, are detail views of the manual devices employed for setting the supplemental bars in different relative positions.

As shown in Fig. 1, the mold wheel A is provided with one or more slug casting molds A¹, which are adjustable both as to length and width of the mold slot or cavity. Ordinarily, four molds of different sizes are mounted on the wheel, and the latter is manually adjusted to bring any selected mold into use. As before intimated, the selected mold may be one for casting a thin or thick slug. The thin slugs are usually of the plain or solid variety, whereas the thicker slugs are usually of the ribbed or recessed variety as shown in Figs. 2 and 3, where it will be seen that the ribbed slug therein illustrated comprises a solid body portion 1, an overhanging type-carrying portion 2, and a series of ribs 3 cast on the side of the body portion and giving support to the overhanging portion. The mold A¹ for casting such a ribbed slug is of course shaped or fashioned to correspond, it being sufficient to say that the ribs 3 are cast in fore-and-aft grooves formed in the cap portion of the mold. If any further information is desired as to the form of con-

struction of the mold and slugs, reference may be had to the Hall patent, No. 665,212.

The mold wheel A (see Fig. 3) is mounted for rotation upon the lateral arm A² of a fore-and-aft mold slide A³, which latter is moved forwardly and backwardly in suitable guideways to carry the active mold into and out of contact with the composed matrix line, all in the usual way.

Coming now to the present invention, and referring first to the embodiment illustrated in Figs. 1 to 7, the improved ejecting mechanism includes, as usual, a fore-and-aft actuating slide B mounted for reciprocation in the mold slide A³ and operated in the regular way thru a connecting link B¹ from the main drive shaft of the machine. The ejector proper is made up of the main section C which may be used alone when casting thin slugs, and a supplemental section D which may be used conjointly with the main section when casting thicker slugs of the ribbed variety. Both sections are freely adjustable in width to correspond to slugs of different lengths.

The main ejector section C is similar in all respects to the regular ejector as used in the commercial linotype machine, or as illustrated in the Rogers patent before referred to. Thus, it comprises a series of vertically disposed blades C¹ arranged edge to edge in contacting relation, a corresponding series of horizontally disposed slides C², and a vertically adjustable bar C³ which controls the connection of the ejector blades to and from the actuating slide B. The ejector blades C¹ and their slides C², are both supported in the mold slide A³ in the usual manner, the slides being freely movable in fore-and-aft grooves formed in the side face of the mold slide, as shown. At their forward ends, the slides C² are provided with rectangular lugs c which fit into corresponding holes or openings formed in the rear ends of the ejector blades; and at their rear ends, the slides C² are provided with similar rectangular lugs c¹ for engagement with the forward edge of the vertically adjustable bar C³. The bar C³ (also as usual) is mounted to slide vertically in a grooved guideway c² formed in the actuating slide B, the opposite edges of the groove snugly engaging the opposite edges of the bar so that the latter is caused to move forwardly and backwardly with the actuating slide. At its lower end, the bar C³ is slidably supported upon a long fore-and-aft rod C⁴ carried by a vertically adjustable slide C⁵ operated by a hand lever C⁶ extended to the front of the machine.

By means of the above arrangement (all of which is fully disclosed in the Rogers patent), the bar C³ may be set in different vertical positions to connect any desired number of blades C¹ with the actuating slide B. Thus, as shown in Fig. 2, the bar C³ is set to connect eleven of the blades C¹ (counting

from the bottom) to the actuating slide B, leaving the three uppermost blades free or disconnected from the slide. Hence, when the slide B is moved forward to expel the cast slug from the mold, the bar C³ is moved with it, its forward edge engaging the lugs c¹ on the rear ends of the appropriate slides C², which latter are thus pushed forwardly to actuate the selected ejector blades (see Fig. 4). During the return stroke of the actuating slide B, a shoulder c³ formed thereon in advance of the lugs c¹ engages the latter and by such engagement draws back the slides C² and the connected ejector blades C¹ (see Fig. 3).

Referring now to the supplemental ejector section D, it is an entirely new element added to the machine, comprising a series of blades D¹ disposed horizontally in superposed parallel relation alongside the main blades C¹. Since these blades D¹ are designed only to engage the ribs 3 of the cast slugs, they do not need to be arranged in face to face contact, but are spaced apart to agree with the spacing of the slug ribs, which may be uniform or otherwise. Due to the wider spacing of the blades D¹, their number is only half that of the main blades C¹, there being one supplemental blade D¹ for every other main blade C¹.

Being disposed flatwise, the blades D¹ do not require the use of separate actuating slides, such as the slides C² for the main blades, and instead they are made long enough to extend from the forward ends of the main blades C¹ to the adjustable bar C³ so as to be operated directly by the latter or the supplemental bar which it carries. At their forward ends the blades D¹ are slidably supported in horizontal guides formed in a block or rack A⁴ attached to the mold slide A³, and at their rear ends, the blades are similarly supported in horizontal guides d¹ formed in the forward end of the actuating slide B. The tongues B² left on the slide B by the formation of the guides d¹ are cut away at the side, as at B³, to clear the rack A⁴ when the slide is advanced for the ejection of the slug (see Fig. 3).

The selection of the blades D¹ is controlled by a second or supplemental vertically adjustable bar D³ dove-tailed to the main bar C³ (Fig. 3). This supplemental bar D³, like the main bar C³, is slidable at its lower end upon the supporting rod C⁴ and hence will be adjusted upwardly and downwardly with the bar C³ when the hand lever C⁶ is operated. However, the supplemental bar D³ is intended to have an independent vertical movement relative to the main bar C³, and to this end, the supporting rod C⁴ is provided with a rotary cam or eccentric D⁴ arranged in engagement with an arm D⁵ extending laterally from the lower end of the bar D³ (see particularly Figs. 5 and 6). As will be evident, when the eccentric is turned in one direction, it will shift the bar D³ to its upper position

- relatively to the bar C^3 , as in Fig. 5, whereas when the eccentric is turned in the opposite direction, it will shift the bar D^3 to its lower position relatively to the bar C^3 , as in Fig. 6. 5 To insure the lowering of the bar D^3 in the latter operation, there is employed a compression spring D^6 which is anchored at one end in the bar C^3 and which presses downwardly at its free end on the arm D^5 . A pair of handles D^7 is employed for the turning of the eccentric, and a stop pin D^8 mounted on the bar C^3 serves in cooperation with the handles to limit the rotation of the eccentric in opposite directions. 10
- 15 As shown in several of the figures, the main bar C^3 is formed in its outer side face with a series of fore-and-aft cuts or grooves c^4 , one for each of the supplemental ejector blades D^1 , and the supplemental bar D^3 is formed in 20 its outer side face with a similar series of cuts or grooves d^4 . In the different adjusted positions of the bar C^3 , the grooves c^4 are arranged to aline with the supplemental ejector blades D^1 , so that the bar in moving toward with the actuating slide B will clear the supplemental blades and act only upon the slides C^2 for the main blades C^1 . 25
- 30 The relative adjustment of the bar D^3 is intended to permit or prevent such clearance between the bar C^3 and the supplemental ejector blades D^1 . Thus, when the bar D^3 occupies its lower position in relation to the bar C^3 , the grooves d^4 stand in register with the grooves c^4 and hence neither bar will engage the supplemental blades D^1 when the actuating slide B is moved forwardly (see Fig. 6). On the other hand, when the bar D^3 occupies its upper position in relation to the bar C^3 , the grooves c^4 will stand out of register with the grooves d^4 , and hence when the slide B is moved forwardly, the solid portions of the bar D^3 (which now stand across the grooves c^4 , see Figs. 2 and 5), will engage the rear ends of the blades D^1 and thus push 40 the blades forwardly (see Fig. 4). 45
- 50 In this connection, it may be noted that the lugs c^1 of the slides C^2 are disposed forwardly of the solid edge of the bar C^3 , with which they always engage, for a distance about equal to that between the solid edge portion of the bar D^3 and the rear ends of the blades D^1 , so that as a result the two ejector sections will be operated in proper unison. 55
- 55 In providing for the return of the supplemental blades D^1 after actuation by the slide B, the blades are formed intermediate of their length with down-turned portions or lugs d^5 (see Figs. 2 and 7) which are located behind lugs c^5 formed on the slides C^2 for the main ejector blades C^1 , or at least those slides C^2 associated with the supplemental blades D^1 . 60
- 65 From the foregoing description, it will be seen that the improved ejecting mechanism comprises a composite ejector which, while 65 permanently mounted in the machine, can be altered at will both in thickness and in width. The variation in width of the two ejector sections is effected simultaneously by the operation of the common hand lever C^6 thru the medium of the bars C^3 and D^3 which are movable upwardly or downwardly in unison in selecting the number of blades desired. The use of the main section alone or of both sections conjointly is controlled simply by adjusting the supplemental bar D^3 with the aid of the eccentric D^4 , which when set in one position enables both bars C^3 and D^3 to clear the supplemental blades D^1 , but which when set in the other position causes the supplemental bar D^3 to pick up the supplemental blades D^1 at or about the time that the main bar C^3 picks up the main blades C^1 . 70
- 75 The modification illustrated in Figs. 9 to 14 differs from the first embodiment only in the respect that a second supplemental ejector section E has been added. The main section C and the supplemental section D are the same as before described, and the parts are indicated by the same letters of reference, so that no further explanation is required. 80 As to the second supplemental section, it is here shown as comprising a series of blades E^1 disposed horizontally in edge to edge contact with the blades D^1 of the first supplemental section. 85
- 90 The blades E^1 are supported in a manner similar to the blades D^1 and are controlled in use by a third vertically adjustable bar E^3 dove-tailed at its upper and lower ends to spacing blocks E^2 attached to the bar D^3 100 (see Fig. 9). Like the bars C^3 and D^3 , the bar E^3 is slidable on the supporting rod C^4 and is adjustable relatively to the bars C^3 and D^3 by a rotary cam or eccentric E^4 having operating handles E^7 cooperating with a stop pin E^8 , which in this instance serves as a stop for the handles D^7 of the eccentric D^4 controlling the second bar D^3 . In this instance, too, the bars D^3 and E^3 are normally urged downwardly and held in their 105 lower positions by tension springs E^6 pulling downwardly on the bars from a fixed pin projecting from the bar C^3 . To complete the detail description, it is merely necessary to point out that the bar E^3 is formed with transverse cuts or grooves e^4 which may be shifted into and out of register with the blades E^1 . 110
- 115 It is intended that the supplemental blades E^1 be used only when the supplemental blades D^1 are in use, and to bring that about, the eccentrics D^4 and E^4 are mutually formed to insure their proper cooperation. As best shown in Figs. 12, 13, and 14, the hub of the eccentric E^4 for the third bar E^3 is mounted to rotate about the extended hub portion of the eccentric D^4 for the second bar D^3 . The eccentric hub E^4 is formed with a lug E^9 arranged to engage a lug D^9 on the eccentric hub D^4 . When both bars D^3 and E^3 are in 120 125 130

their lower positions, as shown in Figs. 8 and 9 with their eccentrics both facing downwardly, the lugs are in engagement as indicated in Fig. 12. Now if it were desired to 5 use the supplemental blades D¹ conjointly with the main blades C¹, but without the supplemental blades E¹, the eccentric D⁴ is rotated to elevate the bar D³ alone, the lug D⁹ breaking contact with the lug E⁹ and 10 leaving the eccentric E⁴ undisturbed (see Fig. 13). If later it should be desired to bring into use the second supplemental set 15 of blades E¹, then the eccentric E⁴ is rotated to elevate the bar E³, leaving the eccentric D⁴ undisturbed and bringing the lug E⁹ again into contact with the lug D⁹ (see Fig. 14). By operating the eccentrics E⁴ and D⁴ in reverse manner, the supplemental blades E¹ may first be disconnected from the 20 actuating slide B and then the supplemental blades D¹. If both sets of supplemental blades are to be disconnected from the actuating slide, this can be accomplished at one 25 operation by turning the eccentric D⁴ back to its original position, as under such circumstances the lug D⁹ will engage the lug E⁹ and cause the rotation of both eccentrics in unison. In similar fashion, if both sets of supplemental blades are to be connected to 30 the actuating slide, this can be accomplished by turning the eccentric E⁴ alone, since in such turning the lug E⁹ will engage the lug D⁹ and effect the rotation of both eccentrics together for the simultaneous raising of the 35 two bars D³ and E³. Stated differently, the rotation of the eccentric E⁴ for the raising of the bar E³ will simultaneously effect the rotation of the eccentric D⁴ in the event that the latter has not already been operated for 40 the raising of the bar D³, so that in no case will it result that the second supplemental set of ejector blades can be used without the first supplemental set.

Since both supplemental sets of ejector blades are used together, the return of the blades E¹ may be readily effected by the simple expedient shown in Fig. 10, where it will be seen that the blades E¹ are formed at their rear ends with laterally extending 50 lugs e engaged in notches e¹ formed in the corner edges of the blades D¹. The blades D¹ are thus free to move forwardly without the blades E¹ but will act to return the latter blades when the two sets are used conjointly. 55 Having thus described my invention, what I claim is:

1. In or for a slug casting machine, a slug ejecting mechanism having an ejector properly permanently mounted in the machine, means 60 for varying the effective width of the ejector, and separate means for varying the effective thickness of the ejector.
2. In or for a slug casting machine, a slug ejecting mechanism comprising a main 65 ejector section, a supplemental ejector sec-

tion arranged alongside thereof to increase the effective thickness of the ejector as a whole, and selective means for bringing into action one section alone or both sections conjointly, as required. 70

3. In or for a slug casting machine, a slug ejecting mechanism comprising a main ejector section, a supplemental ejector section arranged alongside thereof to increase the effective thickness of the ejector as a whole, and means for selecting the main ejector section for independent use or for selecting both the main and supplemental sections for conjoint use, as required. 75

4. In or for a slug casting machine, a slug ejecting mechanism comprising a main ejector section, a supplemental ejector section arranged alongside thereof to increase the effective thickness of the ejector as a whole, a common actuating slide, and means for connecting one section alone or both sections conjointly to the actuating slide. 80

5. In or for a slug casting machine, a slug ejecting mechanism comprising a main ejector section, a supplemental ejector section arranged alongside thereof to increase the effective thickness of the ejector as a whole, a common actuating slide, and means for connecting the main ejector section alone or both sections conjointly to the actuating slide. 90

6. A slug ejecting mechanism according to claim 2, including means for varying the effective width of the supplemental ejector section as well as that of the main ejector section. 100

7. A slug ejecting mechanism according to claim 2, including unitary means for effecting a corresponding adjustment in width of the two ejector sections.

8. A slug ejecting mechanism according to claim 2, characterized by the fact that the main ejector section is in the form of a series of blades arranged edge to edge, and that the supplemental ejector section is in the form of a series of blades arranged face to face. 105

9. A slug ejecting mechanism according to claim 2, characterized by the fact that the main ejector section is in the form of a series of blades arranged edge to edge in contacting relation, and that the supplemental ejector section is in the form of a series of blades arranged face to face in spaced relation. 115

10. In or for a slug casting machine, a slug ejecting mechanism comprising two sets of ejector blades arranged side by side, a common actuating slide, and means for connecting one set alone or both sets conjointly to the actuating slide. 120

11. In or for a slug casting machine, a slug ejecting mechanism comprising a main set of ejector blades disposed vertically edge to edge in a common vertical plane, a supplemental set of ejector blades disposed horizontally in superposed parallel relation alongside the main blades, a common actuating slide, and 125 130 135

means for connecting the main set alone or both sets conjointly to the actuating slide.

12. In or for a slug casting machine, a slug ejecting mechanism comprising a main set of 5 ejector blades disposed vertically edge to edge in a common vertical plane, a supplemental set of ejector blades disposed horizontally in superposed parallel relation alongside the main blades, a common actuating 10 slide, and means for connecting different selected numbers of blades of the two sets to the actuating slide, said means being operable to disconnect the supplemental set of blades 15 entirely from the actuating slide, while leaving the main set of blades connected thereto.

13. In or for a slug casting machine, a slug ejecting mechanism comprising a main set of 20 ejector blades disposed vertically edge to edge in a common vertical plane, a supplemental set of ejector blades disposed horizontally in superposed parallel relation alongside the main blades, a common actuating slide, and means operative under one setting of the 25 parts for connecting any selected number of blades of the main set alone to the actuating slide and operative under a different setting of the parts for connecting to the slide conjointly with said selected main blades a corresponding number of supplemental blades, 30 whereby the ejector proper may be varied both as to width and thickness.

14. In or for a slug casting machine, a slug ejecting mechanism comprising a main set of 35 ejector blades disposed vertically edge to edge in a common vertical plane, a supplemental set of ejector blades disposed horizontally in superposed parallel relation alongside the main blades, a common actuating slide, a main vertically adjustable bar for connecting 40 any selected number of main blades to the actuating slide, and a supplemental bar adjustable with the main bar for connecting a corresponding number of supplemental blades to the actuating slide, said supplemental 45 bar being adjustable independently of the main bar to disconnect the supplemental blades from the actuating slide when desired.

15. In or for a slug casting machine, a slug ejecting mechanism comprising a main set of 50 ejector blades disposed vertically edge to edge in a common vertical plane, a supplemental set of ejector blades disposed horizontally in superposed parallel relation alongside the main blades, a common actuating slide, a main vertically adjustable bar controlling the 55 connection of the main blades to the actuating slide and formed in its side face with fore-and-aft cuts or grooves to clear the ejector 60 blades of the supplemental set, and a supplemental bar carried by the main bar and controlling the connection of the supplemental blades to the actuating slide, said supplemental bar being likewise formed with fore-and-aft 65 cuts or grooves and adjustable relatively

to the main bar to locate the cuts or grooves of the two bars in or out of register.

16. In or for a slug casting machine, a slug ejecting mechanism comprising a main set of 70 ejector blades disposed vertically edge to edge in a common vertical plane, a supplemental set of ejector blades disposed horizontally in superposed parallel relation alongside the main blades, a common actuating slide, a main vertically adjustable bar movable with the 75 actuating slide and controlling the connection of the main blades thereto, a vertically adjustable supporting rod on which said bar is 80 slidable, a supplemental vertically adjustable bar controlling the connection of the supplemental blades to the actuating slide, said supplemental bar also being slidable on the supporting rod, and means carried by the supporting rod and connected to the supplemental bar for setting it in one or the other 85 of two different positions relatively to the main bar, whereby the supplemental blades may be left entirely free of the actuating slide or a corresponding number actuated conjointly 90 with the selected main blades. 90

17. In or for a slug casting machine, a slug ejecting mechanism comprising a main ejector section, two supplemental ejector sections arranged alongside thereof to increase the 95 effective thickness of the ejector as a whole, and selective means for bringing into use the main section alone or that section conjointly with one or both supplemental sections, as required. 100

18. In or for a slug casting machine, a slug ejecting mechanism comprising a main ejector section, two supplemental ejector sections arranged alongside thereof to increase the effective thickness of the ejector as a whole, a common actuating slide, and means for connecting to the actuating slide the main section alone or that section conjointly with one or both supplemental sections, as required. 105

19. In or for a slug casting machine, a slug ejecting mechanism comprising a main set of 110 ejector blades, two supplemental sets of ejector blades arranged alongside thereof, a common actuating slide, and means for connecting to the actuating slide the main set of blades alone or that set conjointly with one or both of the supplemental sets, as required. 115

20. In or for a slug casting machine, a slug ejecting mechanism comprising a main set of 120 ejector blades disposed vertically edge to edge in a common vertical plane, a supplemental set of ejector blades disposed horizontally in superposed parallel relation alongside the main blades, a second supplemental set of 125 ejector blades arranged horizontally edge to edge with the blades of the first supplemental set, a common actuating slide, and means for connecting to the actuating slide the main set of blades alone or that set of blades conjointly with one or both of the supplemental sets, as required. 130

21. In or for a slug casting machine, a slug ejecting mechanism comprising a main set of ejector blades disposed vertically edge to edge in a common vertical plane, a supplemental set of ejector blades disposed horizontally in superposed parallel relation alongside the main blades, a second supplemental set of ejector blades arranged horizontally edge to edge with the blades of the first supplemental set, a common actuating slide, a main vertically adjustable bar for connecting any selected number of main blades to the actuating slide, a supplemental bar adjustable with the main bar for connecting a corresponding number of blades of the first supplemental set to the actuating slide, a second supplemental bar also adjustable with the main bar for connecting a corresponding number of blades of the second supplemental set to the actuating slide, and means for setting the supplemental bars in different positions relatively to the main bar and to each other, whereby the main set of blades alone or that set conjointly with the first or second supplemental sets of blades 25 may be connected in different numbers with the actuating slide.

22. A slug ejecting mechanism according to claim 21, characterized by the fact that the several vertically adjustable bars therein referred to are all movable with the actuating slide and are slidably supported on a vertically adjustable rod by which their adjustment is effected, and that the setting means for said bars is also mounted on the vertically adjustable supporting rod.

23. In or for a slug casting machine, a slug ejecting mechanism comprising a main ejector section, two supplemental ejector sections arranged alongside thereof to increase the effective thickness of the ejector as a whole, selective means for bringing into use the main section alone or that section conjointly with one or both supplemental sections as required, and means for preventing the selection of the second supplemental ejector section without selecting the first supplemental ejector section.

24. In or for a slug casting machine, a slug ejecting mechanism comprising a main ejector section, two supplemental ejector sections arranged alongside thereof to increase the effective thickness of the ejector as a whole, selective means for bringing into use the main section alone or that section conjointly with one or both supplemental sections as required, and means whereby the selection of the second supplemental ejector section will automatically effect the selection of the first supplemental ejector section.

25. A slug ejecting mechanism according to claim 21, characterized by the fact that the second supplemental ejector section is useable conjointly with both the main and first supplemental ejector sections only.

26. In or for a slug casting machine, a slug

ejecting mechanism permanently mounted in the machine and adjustable to provide a ribless ejector proper or a ribbed ejector proper, as required.

27. In or for a slug casting machine, a slug ejecting mechanism permanently mounted in the machine and adjustable to provide a ribless ejector proper of any desired width or a ribbed ejector proper of any desired width, as required.

28. In or for a slug casting machine, a slug ejecting mechanism permanently mounted in the machine, means operable at will for adjusting the ejecting mechanism to provide an ejector proper with or without ribs, and means operable under either of said adjustments for varying the effective width of the ejector proper.

29. In or for a slug casting machine, a slug ejecting mechanism permanently mounted in the machine and having an ejector proper variable in thickness, and means for varying the effective width of said ejector proper while maintaining its thickness unchanged.

30. In or for a slug casting machine, a slug ejecting mechanism permanently mounted in the machine and having an ejector proper variable in width, and means for varying the effective thickness of said ejector while maintaining its width unchanged.

In testimony whereof, this specification has been duly signed by:

FRANK C. FROLANDER.
